UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LENO MOTION FOR LOOMS.

Application filed June 2, 1927. Serial No. 196,113.

This invention relates to improvements in leno motions for looms and the principal object thereof is to provide a motion which will produce a more accurate leno weave.

In leno or cross weaving looms, as is well known, the warp threads are given a relatively lateral or transverse movement to cause one warp thread to cross over an adjacent warp thread after the heddles have been relatively moved vertically sufficiently to permit such transverse movement; then the relative vertical movement of the heddles is reversed to form the shed to receive the weft or filling thread.

In usual types of looms the transverse movement of the heddles or heddle frames is produced by the oscillation of a rock shaft or rock shafts having arms pivotally attached to the ends of the heddle frames so that the transverse movement of the heddle frames includes a swinging movement instead of a true vertical movement. This swinging of the heddle frames forward and backward interferes with the exactness of the leno weave.

One of the objects of the present invention is to provide means for causing both the vertical and transverse movements of the respective heddle frames to take place in true vertical planes.

A further object of the invention is to provide means for co-ordinating accurately the relative transverse movements of the heddles, thereby further insuring accuracy in the leno weave.

In usual types of looms for producing leno weave the mechanism, which produces the transverse movements of the heddles, is rendered relatively slow by reason of the arc through which the frames are swung backwardly and forwardly so that special cams provided with long dwells are required to actuate the treadles which move the heddles vertically. By the provision of means for causing the heddles to reciprocate both vertically and transversely in a true vertical plane, much more rapid shifting of the heddles transversely is permitted which will enable the vertical movement of the heddles to be produced by the usual types of treadle cams which are employed in plain weave.

The employment of such usual types of cams in leno looms reduces to a considerable extent the vibration of the loom over that which takes place when the special cams,

which are more or less of rectangular form, 55 are employed.

Other objects and features of the invention will more fully appear from the following description and the accompanying drawings and will be particularly pointed out in 60 the claims.

Inasmuch as the present invention relates only to improvements in mechanism for actuating the heddles of a leno motion, only so much of the loom need be illustrated as is 65 required to show the application of the invention thereto.

A preferred embodiment of the invention is shown in the accompanying drawings, in which, 70

Fig. 1 is a side elevation of a loom including the loom side, and the lay, the harnesses or heddles for producing leno weave, and the mechanism for actuating the same;

Fig. 2 is a detail plan view of the heddle- 75 actuating mechanism; and,

Fig. 3 is a detail front elevation showing particularly the mechanism for transmitting transverse relative movement to the heddle frames. 80

The loom, which may be of the usual type, comprises loom sides 1 and 2, upon which the mechanisms of the loom are mounted, including the lay sword 3 which is pivotally mounted at its lower end upon the lay rocker shaft 4 and is provided at its upper end with the usual lay 5 and reed 6, the lay sword being actuated through a pitman 7 from a crank (not shown) upon the usual crank shaft 8 of the loom. The loom sides are provided centrally with vertical standards 9 having at their upper ends forwardly extending arms 10 having journals 11 for the shaft upon which the harness-supporting rolls 12 are mounted. The loom harness comprises 90 front and rear heddle frames 13 and 14 which are supported by straps 15 which pass over the rolls 12. The lower ends of the heddle frames are connected by straps 16 and 17 to treadles 18 and 19 which are pivotally mounted upon a shaft 20 at the rear of the loom and are actuated by cams 21 and 22 upon the auxiliary cam shaft 23 of the loom. 95

The cams 21 and 22 are symmetrical and are so disposed as to oscillate the treadles 18 and 19 alternately vertically thereby imparting vertical relative movement to the heddle frames in the usual manner. 100 105

The auxiliary cam shaft is driven by a gear 24 from a complementary gear 25 of like pitch upon the cam shaft 26 of the loom while the cam shaft 26 is driven through a gear 27 of 5 twice the diameter or pitch of the gear 24 by a gear 28 on the crank shaft 8, the gear 28 being of half the diameter of the gear upon the cam shaft.

By reason of this construction the heddles 10 are moved alternately up and down upon each beat-up of the lay as in usual loom constructions. By reason of the mechanism for imparting a rapid transverse movement to the heddle frames, hereinafter to be described, 15 the present invention enables the use of the usual substantially lobe-shaped cams in the place of the special rectangular cams heretofore employed in looms of this type.

The present invention in its broad sense 20 comprises means for moving the heddle frames transversely provided with means for also maintaining the heddle frames in a true vertical plane during both the vertical and horizontal reciprocation thereof.

25 The harnesses illustrated herein comprise front and rear heddle frames 13 and 14 of usual rectangular form, the front heddle frame having top bars 31 and bottom bars 32, in which the heddles are mounted, connected 30 by vertical end bars 33 and 34. In the construction illustrated herein the heddles comprise a series of plain heddles or dents 35 which extend from the top heddle bar 31 to the bottom heddle bar 32 of the front frame 35 with loop needles 36 mounted in the bottom heddle bar intermediate of the dents 35 and extending approximately half the length thereof, provided at their upper ends with eyes 37 to receive alternate warps, other 40 warps lying freely in the spaces between the plain heddles or dents 35, in the usual manner. The rear heddle frame 14 is reversely constructed and the vertical end bars 33 and 39 are arranged in juxtaposition and preferably 45 in engagement with the vertical end bars 33 and 34 of the front heddle frame. Each of the end bars of the heddle frames is provided with vertical guideways which, in the construction illustrated herein, are in the form 50 of angle bars 40 and 41 attached to and extending longitudinally of the vertical end frames 33 and 34 of the front heddle frame and similar angle bars 42 and 43 which are connected to the end bars 38 and 39 of the 55 rear heddle frame. Transverse rectilinear movements are imparted to these heddle frames by actuating members which move in the vertical plane of the movement of the heddle frames.

60 In the particular construction illustrated herein arms 44 and 45 are pivotally mounted upon a shaft 46 carried in a bearing block 47 which is secured by a bolt 48 to a bracket 49 extending inwardly from the loom side, approximately at mid-position of the heddle

frames. The arms 44 and 45, as shown in the drawings, are inverted L-shaped in form, and the free ends are provided with cylindrical end portions 50 and 51 which engage respectively within angles of the guides 40 70 and 42. The arms 44 and 45 are spaced apart in such a manner as to hold the adjacent vertical ends 33 and 38 of the front and rear heddle frames in sliding engagement.

Suitable means are provided to oscillate 75 the arms 44 and 45 in the vertical plane of the movement of the heddles produced by the action of the treadles of the loom and these arms serve not only to impart transverse movement to the heddles, but also as guides to insure true vertical movement of the heddle frames.

80 The arms 44 and 45 are oscillated to impart the transverse movement to the heddle frames by links 52 and 53 which are adjustably connected to the arms 44 and 45 by bolt and slot connections 54, the opposite ends of the arms 52 and 53 being pivotally connected to vertical posts 55 and 56 which are swiveled in 85 the ends of oppositely extending arms of a T-shaped plate 57 which is pivotally mounted upon a stud 58 extending upwardly from a bracket 59 which is mounted upon the bracket 49 which is carried by the loom side. A link 60 is pivotally connected at one end 90 to the stem 61 of the T-shaped member 57 and at its opposite end is pivotally connected to a stud 62 projecting upwardly from the end of a rocker arm 63 which is pivotally mounted centrally of its length upon a stud 64 projecting from a bracket 65 carried by the loom side and is provided at its lower end with a pivotally mounted cam follower 66 adapted to travel in the grooves of a switch cam 67 which may be conveniently 95 mounted upon a take-up shaft 68 of the loom. The take-up shaft is driven at the same rate of speed as the cam shaft by beveled gears 69 and 70 mounted respectively upon the cam shaft and the take-up shaft.

100 The reversing portions of the grooves of the switch cam 66 are such as to impart quick transverse movement to the heddle frames and are so timed with respect to the vertical movement of the heddles that full transverse movements of the heddles will have been completed before the weft is laid in the shed produced by the vertical action of the heddles. This quick shifting of the heddles is permitted because of the mechanism which 105 causes the heddle frames to move transversely in the same vertical plane as the vertical movement thereof and no delay is required for the positioning of the heddles in the vertical plane of reciprocation thereof, as has heretofore been necessary where the transverse movement of the heddles has included also a forward and backward movement.

110 The preferred mechanism for moving the heddles transversely and for guiding the 115

same in a vertical plane during such movement also comprises guiding means at the opposite end of the heddle frames which also serve to co-ordinate the transverse movements of the heddles and insure the accuracy of such movement. In the preferred embodiment of the invention disclosed guides 71 and 72 engage respectively the vertical guideways formed by the channel bars 41 and 43 in 5 the ends of the heddle frames 13 and 14 respectively. These guides are in the form of rectangular bars, the shanks 73 and 74 of which are guided in suitable ways in a bracket 75 which is mounted upon a stand 10 76 carried by the loom side 2. The shanks 73 and 74 of these guides are provided with oppositely positioned racks 77 and 78, the teeth of which engage the teeth of a pinion 79 located intermediate of said racks and rotatably mounted upon a stud 80 upon the bracket 75. By reason of this construction positive transverse movement imparted to one of the heddle frames will be transmitted through the rack and pinion to the other heddle frame to move such frame in the opposite direction, for example, when the arm 44 is rocked (to the right from the position illustrated in Fig. 3) the front heddle frame is moved to the right. The guide 71 of the 15 frame is thereby moved to the right, thus causing the rack 77 upon its shank 73 to rotate the gear 79. Inasmuch as the gear 79 engages the rack 78 upon the stem 74 of the guide 72 the guide 72 will be moved positively in the opposite direction thus positively forcing the rear heddle to the left simultaneously with the positive movement of the front heddle 29 to the right, thus causing the heddle to follow the movement of the 20 actuating arm 45 which at this time is withdrawn by the action of the movement of the T-shaped actuating member. Thus the relative movements of the front and rear heddles are co-ordinated both as to time and extent of movement. Accuracy of the transverse shifting movements of the heddles is insured, both by reason of this co-ordination and by the maintenance of the heddle frames 13 and 14 in the same vertical planes both 25 during the vertical reciprocation and transverse movement.

As heretofore stated the present mechanism, which insures the reciprocation of the heddles respectively in the same vertical planes both during vertical and transverse movement, permits a quicker transverse shifting of the heddles than in previous heddle-actuating mechanisms in which the heddles were given a swinging movement into 30 and out of the vertical plane of reciprocation so that the treadles for imparting the vertical movement to the heddles may be actuated by usual types of loom cams instead of requiring special substantially rectangular cams such as those which have been hereto-

fore generally employed for actuating the harnesses of leno looms. Much less vibration is, therefore, caused by the use of usual cams. Furthermore, the present invention, which permits the use of the usual treadle 70 cams of the loom, enables the leno mechanism to be more readily applied to usual types of looms without re-organization of the loom.

The invention is illustrated herein as applied to a certain form of plain loom. It 75 will, however, be understood that the invention may be embodied in other types of looms, such as dobbies, pattern, etc.

It will also be understood that various changes in form, construction and arrangement of parts may be made within the spirit 80 and scope of the following claims.

Having thus described the invention, what is claimed as new, and desired to be secured by Letters Patent, is:

1. In a leno loom comprising a pair of heddle frames having suitable means for controlling the warps, and provided with guideways extending longitudinally of the vertical ends of said frames, means for imparting vertical relative movements to said heddle frames, actuating means engaging the respective guideways at one end of said frames reciprocable in the planes of the respective frames and operable to impart relative transverse movements to said frames alternately in one direction and also to prevent said frames from displacement from their respective vertical planes, complementary guiding members movable horizontally in said vertical planes engaging the guideways at the opposite ends of said frames and means for transmitting the actuated movement of one of said complementary members to the other, but in the opposite direction. 95

2. In a leno loom comprising a pair of heddle frames having suitable means for controlling the warps, guideways extending longitudinally of the ends of each frame, means for imparting relative vertical movements to said frames and actuating means for imparting relative transverse movements to said frames alternately in one direction, comprising members engaging the guideways at the same ends of said heddle frames 100 movable in opposite directions in the respective vertical planes of said frames and complementary guiding members engaging the respective guideways at the opposite end of said frames reciprocable in the respective vertical planes of said frames and means operable to transmit the actuated movement of each of the respective frames to the other but in the opposite direction. 115

3. In a leno loom comprising a pair of heddle frames having suitable means for controlling the warps, guideways extending longitudinally of the ends of each frame, means for imparting relative vertical movements to said frames and actuating means 120

for imparting relative transverse movements to said frames alternately in one direction, comprising members engaging the guideways at the same ends of said heddle frames movable in opposite directions in the respective vertical planes of said frames, complementary guiding members engaging the respective guideways at the opposite end of said frames reciprocable in the respective vertical planes of said frames and means for co-ordinating the relative movements of said complementary guiding members operable to transmit the actuated movement of each of the respective frames to the other but in the opposite direction.

4. In a leno loom comprising a pair of heddle frames having suitable means for controlling the warps, guideways extending longitudinally of the ends of each frame, means for imparting relative vertical movements to said frames and means for imparting relative transverse movements to said frames, comprising members engaging the guideways at the same ends of said heddle frames movable in opposite directions in the respective vertical planes of said frames, complementary guiding members engaging the respective guideways at the opposite end of said frames reciprocable horizontally in the respective vertical planes of said frames and provided with oppositely disposed racks and a pinion interposed between and engaging said racks operable to co-ordinate the relative transverse movements of said frames.

5. In a leno loom comprising a pair of heddle frames having suitable means for controlling the warps, guideways extending longitudinally of the ends of each frame, means for imparting relative vertical movements to said frames and means for imparting relative transverse movements to said frames, comprising reciprocable members slidably engaging respectively the guideways at the same ends of said frames, means for moving said members simultaneously in opposite directions and complementary guiding members slidably engaging the respective guideways at the opposite ends of said frame horizontally reciprocable in the vertical planes of said frames and means for co-ordinating the movement of said complementary guiding members operable to transmit the actuated movement of each of the respective frames to the other but in the opposite direction.

6. In a leno loom comprising a pair of heddle frames having suitable means for controlling the warps, guideways extending longitudinally of the ends of each frame, means for imparting relative vertical movements to said frames and means for imparting relative transverse movements to said frames, comprising pivotally mounted members having

their free ends slidably engaging respectively the guideways at the same ends of said frames, means for rocking said members simultaneously in opposite directions, and complementary guiding members slidably engaging the respective guideways at the opposite ends of said frame reciprocable horizontally in the vertical planes of said frames provided with oppositely disposed racks and a pinion interposed between and engaging said racks acting to co-ordinate the relative transverse movements of said frames.

7. In a leno loom comprising a pair of heddle frames having suitable means for controlling the warps, guideways extending longitudinally of the ends of each frame, means for imparting relative vertical movements to said frames and means for imparting relative transverse movements to said frames, comprising pivotally mounted members having their free ends engaging the respective guideways at the same ends of said frames, means for moving pivotally mounted members simultaneously in opposite directions including a switch cam operable to impart a quick movement to said pivotally mounted members upon every other rotation of the crank shaft of the loom and complementary guiding members slidably engaging the respective guideways at the opposite ends of said frames and reciprocable horizontally in the vertical planes of said frames acting to insure true vertical movements of said frames and means for transmitting the actuated movement of each of the respective frames to the other but in the opposite direction.

8. In a leno loom comprising a pair of heddle frames having suitable means for controlling the warps, guideways extending longitudinally of the ends of each frame, means for imparting relative vertical movements to said frames and means for imparting relative transverse movements to said frames, comprising pivotally mounted members having their free ends engaging the respective guideways at the same ends of said frames, means for moving said pivotally mounted members simultaneously in opposite directions including a switch cam operable to impart a quick movement to said pivotally mounted members upon every other rotation of the crank shaft of the loom and complementary guiding members slidably engaging the respective guideways at the opposite ends of said frames and reciprocable horizontally in the vertical planes of said frames provided with oppositely disposed racks and a pinion interposed between and engaging said racks acting to co-ordinate the relative transverse movements of said frames.

In testimony whereof, I have signed my name to this specification.

HARRY A. DAVIS.
